SANITARY PRESERVING CAN

Heinrich Karl, Jersey City, N. J.

Application September 19, 1933, Serial No. 690,088

8 Claims. (Cl. 220—27)

This invention relates to improvements in receptacles and has particular reference to preserving cans.

An object of the invention is to provide an improved can of simple and practical construction, capable of being easily and cheaply manufactured, and which shall be sanitary and embody novel features that permit of the can being opened without the danger of metal filings or particles, entering the contents of the can, thus protecting the consumer of said contents from possible intestinal injury.

Another object is to protect the contents of a can by providing the same with a closure for either or both open ends thereof which embodies an auxiliary protective inner cover adapted to be supported upon the edge of the body of the can which forms said open end, and be held between said edge and outer closure member in such manner that said cover will form an additional hermetical seal for the can, and will not be submerged in said contents, and will effectively prevent any metal particles from falling into the body of the can when said outer closure is being cut to open the can, said cover thereafter providing a removable closure which may be easily placed in position to afford a protective means for said contents when not in use so as to keep the same in a sanitary condition. To provide for the removal of said inner cover, same has a series of convolutions which form pockets into which the finger, or a gripping tool, may be inserted to grip the cover and contract the same so as to withdraw its peripheral edge from between the outer closure member and end of the can body where it is normally held before the outer closure is cut during the operation of opening the can; or, if desired, said inner cover may be torn along said peripheral edge when the cover is gripped as above mentioned. Another object is to construct the auxiliary or inner cover of the can so that it can be contracted and thus enable the peripheral edge thereof to be withdrawn from between the edge of the can body and the outer closure member when it is desired to uncover the contents of the can.

The above and other objects will appear more clearly from the following detailed description, when taken in connection with the accompanying drawings, which illustrate preferred embodiments of the inventive idea.

In the drawings:—

Figure 1 is an elevation of a preserving can

constructed in accordance with one embodiment of the present invention.

Figure 2 is an enlarged fragmentary vertical section substantially on the line 2—2 of Figure 1.

Figure 3 is a fragmentary elevation of one end portion of the body of the can with the end closure removed.

Figure 4 is a view similar to Figure 2 illustrating a slightly different form of end closure.

Figures 5, 6, and 7 are fragmentary sectional views showing different embodiments of end closures and associated can body parts.

Figure 8 is an elevational view of the end closure shown in Figure 7.

Figure 9 is an elevation partly in section of another embodiment of the invention illustrating a different type of end closure from that shown in Figure 1.

Figure 10 is a fragmentary enlarged vertical section through one end of the can illustrated in Figure 9.

Figure 11 is a sectional view showing the application of the end closure in Figure 10 to the body of the can prior to the final operation of clamping the end closure in position.

Figure 12 is a fragmentary perspective view of still another form of can.

Figure 13 is a sectional view of the end closure shown in Figure 12 and,

Figures 14, 15, and 16 are views similar to Figure 13 showing different types of end closures and body constructions for the can.

Referring more particularly to Figures 1 to 3 of the drawings, the can illustrated may be made of any suitable material such as a metal com-

monly employed in the manufacture of receptacles of this kind, the body of the can being indicated by the numeral 20. As is customary, said body is open-ended, and in conformity with the present invention, the open-ended formation of the various modifications of the can bodies may or may not be duplicated at each end of said body, as desired. It will therefore be understood that where, in the following description, reference is made to the particular construction or forma-

tion of the open end of the body or the end closure therefor, such reference is to be construed to include either end of said can body. As shown in Figure 3, from the open end of the body 20 the same is preferably of an outwardly tapered formation, such as indicated at 21, the material of the body being crimped, if necessary, to produce such formation. Adjacent said open end and inwardly of the tapered portion 21 the can

body is provided with a groove 22 one wall of 55

55

the

50

55

which extends diagonally while the adjoining wall is disposed in a horizontal or transverse plane. The edge of the body forming the open end is preferably rolled as indicated at 23 for a purpose which will appear in the course of the description.

The end closure 24 shown in Figures 1 and 2 is of the general type illustrated in my United States Patent #1,691,394, dated November 13, 1928, wherein the depending flange of the closure is provided with a series of flaps which, upon being properly manipulated, permit of the easy removal of the closure from the body of the can. The utilization of these flaps is carried forward in the present invention and, as shown, the flange 25 of the end closure 24 is provided along its free inner edge with an annular series of flaps 26. Between these flaps and the outer end of the closure the flange 25 is provided with an annular 20 detent 27 which, in the form being described, conforms to the contour of the groove 22 in the can body after the closure has been applied to said body. In assembling the elements of the can, it is preferable to apply to the outer wall 25 of the groove 22 or the inner wall of the detent 27, or both, a thin layer of any suitable and desirable binder, indicated at 28 which will effectively secure the body and closure together and hermetically seal the can. In this particular 30 instance the binder 28 is of such a nature that it will not offer undue resistance to the removal of the closure 24 when the various flaps are pulled outwardly with the fingers or by means of a suitable tool, this pulling action being designed 35 to tear the flange 25 across the detent 27 to a point where the closure may be lifted from the body.

In Figure 1, and likewise in Figure 9, the other end of the body 20 is shown as provided with a different type of closure 28 from the closure 24, the former merely having an inturned flange 30 which engages in a groove 31 formed in the tapered end of the body. But, as previously indicated, the two end closures may, if desired, be of exactly the same construction.

50 In my co-pending application #632,735, I have disclosed a novel type of an auxiliary protective covering which is adapted to be interposed between the contents of the can body and the end closures therefor and which primarily acts to catch any loose metal particles which may be formed as the result of opening the end closure by means of cutting tools generally in use, so that said particles will not fall into the contents 55 of the can with possible resultant injury to the consumer of said contents. In said application, various methods of supporting the auxiliary cover in position are illustrated including the provision of an element in addition to the can body and end 60 closure themselves, which element is designed to prevent any possibility of said cover from being submerged in the contents of the can, especially when said contents are of a liquid nature. In accordance with the present invention, there is 65 contemplated a simple and practical method of supporting the auxiliary cover without resorting to the use of any additional supporting means and when said cover is in position the same will provide an additional hermetical seal for the can and may be employed as a removable end closure 70 after the outer closure has been removed and it is desired to protect unused contents of the can against the ingress of dirt or other foreign matter. Thus, the auxiliary cover 32 shown in Fig- 75

ure 2, and which in the other modifications of the invention is of substantially the same construction, is supported, adjacent its peripheral portion, upon the edge 23 of the can body which is rolled, as previously indicated, to prevent the contact of any sharp metallic edge with said cover. It is understood, of course, that the cover 32 is placed in position before the application of the end closure 24 to the can body and it will be seen that after the latter operation said cover will be securely compressed and held between the rolled edge and the main portion of the closure 24 with the outer edge of the cover projecting beyond and overlying the tapered end 21 of said body, thus forming an additional seal between the body and end closure. The cover 32 is made of material having a greater degree of flexibility than that of the material of which the can is made. As examples of the materials which may be employed, there is suggested the use of paper, cellophane, or rubberized cloth coated with any suitable substance which will render the cover impervious to liquids. In making the cover 32 the same is caused to assume a convolute formation in cross section so as to provide the same with a series of concentric depressions or pockets 33 which are preferably reinforced at their bottoms by thickening the material as indicated at 34. This reinforcement is provided to minimize the possibility of the cover being punctured by a cutting tool should the blade thereof be inserted through the end closure 24 directly above the pocket. Said pocket or pockets also form a means of catching and accumulating any metal particles which may be cut from the end closure 24 during the cutting operation and if desired the outer surface of the cover may have applied thereto a thin layer of any suitable adhesive material which will cause said particles to adhere thereto. The convolute form of the cover 32 and consequent provision of one or more depressions therein, presents a means whereby the cover may be easily grasped by the insertion of the fingers and thumb into said depressions when lifting the cover from the end of the can or replacing the same in closing position. In so manipulating the cover, it is apparent that pressure of the fingers against the walls of the convolutions will have the effect of contracting the size of the diameter of the cover so that the peripheral portion thereof may be extracted from between the rolled edge 23 and overlying portion of the end closure should the latter be cut inwardly of the point of contact of said cover with said edge 23.

In Figure 4, the end closure 35 differs from the main closure 24 in that the main portion of the former is of greater diameter and the depending flange 36 is tapered inwardly and of less depth than the flange 26 thereby eliminating the flaps 28. The free edge of the flange 36 is provided with the detent 37 which fits into the groove 22 of the can body and interposed between the two parts is a thin layer of a suitable binder 38. The inward taper of the flange 36 combines with the outwardly tapered portion 21 of the can body to form an annular V-shaped pocket 39 into which metal particles may fall when the closure 35 is cut in the peripheral portion thereof between the point of contact with the inner cover 32 and the outer edge of the end closure. 70

Figures 5 to 7 show various slight modifications in the formation of the can body and the depending flange of the end closure. In Figure 5 the can body is provided adjacent its outer end with an instruck annular groove 48 having three angular

larly disposed walls and the outer end of the body is tapered in the same manner as previously described. The depending flange 41 of the end closure 42 is formed with a V-shaped detent 43 which extends into the groove 40 with a binder 44 disposed in the spaces formed by the different configuration of the groove and detent. In Figure 6 the groove 45 in the can body is substantially semi-circular in form while the detent 46 of the end closure is of channel formation so as to again provide spaces between the same and the outer wall of the groove 45 in which a binder 47 may be disposed. Again, in Figure 7, the groove 48 of the can body and the detent 49 of the end closure are of different configuration, the former being V-shaped while the latter is substantially semi-circular, thus providing spaces between the two in which the binder 50 is placed. In each of the three instances described the operation of applying the end closure to the can body with the binder interposed, compresses the latter so that it will completely fill the spaces formed between the detent and groove and thus securely fasten the end closure in proper position. The three modifications just described are provided with the same kind of an opening means which is illustrated in Figure 8. This means consists of a tongue 51 constituting the extremity of a circumferential strip defined by the score lines 52 one of which extends around the end closure above or outwardly of the groove formation so that when said strip is removed by the turning of the usual type of key-opener which receives the tongue 51, the metal of the detents 43, 46, and 49 will be torn away from the binder to thus loosen the end closure so that it can be removed.

In Figures 9 to 11 another different form of end closure 53 is shown in which the flange 54 thereof is bent upon itself intermediate its edges as indicated at 55 to form an annular pocket or groove to receive the binder 56 just prior to the application of the closure to the can body. The end closure is shown in Figure 11 in its initial position following the application of auxiliary cover 32 to the can body, and if said end closure has been properly placed, the free edge portion of the flange 54 is bent inwardly to the position shown in Figure 10, with another binder 57 interposed between the edge extremity of the flange 54 and the bottom of the groove formed in the can body. With this type of end closure no cutting operation to remove the same is necessary as the now depending portion 55 of the end closure affords a means whereby a tool, such as indicated in broken lines in Figure 10, may be engaged with said portion in such manner that an outward pull thereupon will disrupt the binding between the closure and can body and thus permit of the removal of the former. As indicated by Figure 9, not only the normal top of the can body is provided with the auxiliary cover 32 but a similar cover 58 is also provided for the bottom of the can so that if said bottom should inadvertently be cut instead of the top, as very often occurs, the cover 58 will, in the same manner as previously described, prevent any metal particles from falling into the contents of the can. In both the top and bottom covers 32 and 58 the convolutions therein are so formed that the cover will be provided with a central depression 59. This depression is centrally formed for the purpose of accommodating the point of that type of cutting tool in which the center of a can closure is penetrated by said point to form an axis about which the cutting knife or tool is rotated while it is

severing the end closure adjacent its periphery. With the central depression 59 located directly below the axial point of said tool, said point will not penetrate the cover and the depression will form a pocket into which will fall any metal particles cut from the closure by said point. 5

The can body of Figures 12 and 13 is again of the same construction as that shown in Figure 3 while the end closure 60 is of substantially the same construction as that shown in Figure 2 with the following exceptions. The end flange 61 is of less depth so as to eliminate the flaps 26 so that the free edge of said flange, which also constitutes an edge of the detent 62, is wholly confined within the groove 22 of the can body. Also, the flange 61 above said detent and the main portion of the end closure adjacent its peripheral edge are provided with guiding channels 63 into either of which the blade of a cutting tool may be inserted when removing the end closure. In this form of the invention the auxiliary cover 32 may have a light material 64 such as cotton, placed in the pockets or depressions so as to catch metal particles cut from the end closure, and the peripheral portion of the cover which overhangs 25 the tapered end of the can body may be extended and curved to form small pockets 65 each of which is opposed to one of the guide channels 63 so as to receive cuttings from the end closure. The closure 60 is sealed to the can body by the interposition of a binder 66 between the detent 62 and the wall of the groove 22. 30

In Figure 14 the can body is provided with a groove 67 adjacent its outer end, the walls of which are disposed at an acute angle so that both 35 extend outwardly toward the open end of the can body and inwardly of the wall thereof. This groove 67 is adapted to receive the inturned edge 68 of the flange 69 of the end closure and sufficient space is left between a wall of the groove 40 67 and said edge 68 for the reception of a body of solder or other binder 70.

The end closure of this form may be removed by a cutting tool as previously described. The groove 71 of the form of the can shown in Figure 45 15 has its walls disposed substantially parallel and sufficiently far apart to receive the inturned edge 72 of the flange 73 of the end closure. Said flange is doubled upon itself at 74 to form a pocket and receive a binder 75 and said doubled 50 portion extends outwardly beyond the wall of the can body so as to provide a lip under which the end of a tool, shown in broken lines, may be inserted to remove the end closure in the same manner as described in connection with Figure 55 10.

In Figure 16, the end closure 76 is of greater diameter than the body of the can so that the rim portion 77 of said closure extends beyond the plane of said body. In this rim portion and the 60 depending flange 78 thereof there are provided the guide channels 79 similar to the channel 63 and said flange combines with the tapered end 21 of the can body to form a pocket or chamber 80 into which metal cuttings may fall when the 65 end closure is cut along either of the channels 79. The free edge of the flange 78 is inturned and bent to form the detent 81 which fits into the groove 82 in the can body and the closure is sealed to the latter by interposing a binder 83 70 between said detent and the outer wall of said groove.

What is claimed is:

1. In a preserving can, a body having an open end, a closure for said end, and a flexible contrac- 75

- tile inner cover for said end having its peripheral portion resting upon the edge of the body surrounding said end and interposed between said edge and said closure, said cover having concentric depressions forming means for gripping and contracting the same and also constituting recesses for receiving cuttings from said closure when the latter is being cut open along a line whose vertical plane lies inside said open end.
10. 2. In a preserving can, a body having an open end, a closure for said end, and a flexible contractile inner cover for said end having its peripheral portion resting upon the edge of the body surrounding said end and interposed between said edge and said closure, said cover having concentric depressions forming means for gripping and contracting the same and also constituting recesses for receiving cuttings from said closure when the latter is being cut open, the outer surface of said cover having an adhesive coating.
15. 3. In a preserving can, a body having an open end, said body adjacent said end being tapered, a closure for said open end having an annular flange encircling said tapered end, and an inner cover of convolute form in cross section having its peripheral portion resting upon the edge of said body forming said open end and overhanging the tapered end of said body so as to be held between said edge and a part of said closure.
20. 4. In a preserving can, a body having an open end, a flanged closure for said open end, and an inner cover having its peripheral portion resting upon the edge of said body which forms said open end and held between said edge and the main part of said closure, the size of said closure being such that the rim portion thereof including its flange extends outwardly beyond the plane of the can body, said outwardly extending portion combining with the adjacent end of said body to form an annular chamber disposed exteriorly of the periphery of said inner cover and having a guide channel for receiving a cutting tool.
25. 5. In a preserving can, a body having an open end and provided adjacent said end with a circumferential groove, a closure for said open end having an annular flange a portion of which is inturned into said groove to secure the closure in closing position, said flange being bent upon itself contiguous to said portion to form a pocket for receiving a binder, and said bent portion of the flange acting as a means with which a tool may be engaged when removing the cover from the can body.
6. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
10. 7. In a preserving can, a body having an open end, an outer closure member for said end, and a flexible inner cover made of paper, said cover having a peripheral portion resting upon the edge of said body forming said open end and held in such position by compression between said outer closure member and said edge, and said cover further having convolutions forming concentric channels therein the bottoms of which are spaced sufficiently from said outer closure to prevent puncture of said bottoms by a cutting tool inserted through said closure member, and said channels forming pockets to receive cuttings from said closure member.
15. 8. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
20. 9. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
25. 10. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
30. 11. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
35. 12. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
40. 13. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
45. 14. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.
50. 15. In a preserving can, a body having an open end, an outer closure member for said end, and an inner non-metallic cover for said end having a peripheral portion resting upon the edge of said body forming said open end and held in such position by said outer closure member, said cover having convolutions forming concentric channels therein the bottoms of which are spaced sufficiently from said outer closure to prevent puncture of said bottoms by a cutting tool inserted through said closure member, and said channels forming pockets to receive cuttings from said outer closure member.

HEINRICH KARL.
